TRAIN DISPATCHING SYSTEM FOR RAIL-ROADS

Forest B. Hitchcock and Oscar H. Dicke, Rochester, N. Y., assignors to General Railway Signal Company, Rochester, N. Y.

Application March 9, 1929, Serial No. 345,667

24 Claims. (Cl. 246—3)

This invention relates to a train dispatching system of the type, in which the dispatcher can control distant switch machines, and in which trains are dispatched by wayside signal indications, and in which the indications controlling the signals and switch machines, and indications of the progress of trains, are transmitted over a comparatively few line wires, by apparatus of the synchronous selector type.

In order that a dispatcher may properly dispatch the movement of trains, he should have control over the switch machines and signals, such that they may be moved in rapid succession, which results in the necessity that he should from time to time be informed as to the progress of said trains along the track. This indication of train progress is known in signal parlance as OS-ing train movements. It is understood by those skilled in railway practice, that OS indications may come in simultaneously and in closely spaced or overlapped relations, and for this reason a synchronous selector type system, for transmitting such OS information, lends itself to this function admirably, this being because a synchronous selector type system permits the transmission of a very large number of distinctive indications over the same line wire within a very short period of time.

However, there are limitations to the extent to which a synchronous selector of the rotary arm type may be used. This is because there is a limit to the size to which a rotary selector may be built, thus limiting the number of what we shall term message channels, also the necessity for speed, limits the size or compactness, as well as the ruggedness that may be built into such a selector. Also, such selectors must be built for a given number of message channels, which means that a need for additional channels, would require all existing selectors to be replaced by new ones.

In view of the above considerations and others, it is proposed to use for dispatching purposes in accordance with the present invention, a self-stepping synchronous selector system, in which the rotary arm selector, such as set forth in the patent to R. C. Leake, Patent No. 1,794,628 dated March 3, 1931, is replaced by a sufficient number of relays, both in the dispatcher's office and in each way-station, to set up the required number of message channels. In accordance with the present invention, it is proposed to transmit a plurality of alternate positive and negative impulses over the stepping circuit, including the stepping wire and the common return wire, of

which, each impulse will energize and move one of the above mentioned relays in the dispatcher's office and one in each way-station, and during that period of time which exists between the movement of two successive relays, either a control indication from the dispatcher's office, or an OS indication may be transmitted over the message channel then set up. The arrangement of this system is preferably such as to permit it to be at rest a large part of the time. It is proposed to start the system from rest by a distinctive long positive impulse sent over the stepping wire, which impulse is subject to initiation from either the dispatcher's office or from any way-station, and also, the system as proposed, stops automatically at the end of the period of time that is required to transmit all of the indications, which period of time may be no shorter than two complete cycles. Other features of the present invention reside in the construction and arrangement of parts to establish synchronism between the banks of message channel selecting relays at various way stations and with the dispatcher's bank of message channel selecting relays, as well as the added feature of a novel circuit, so arranged, as to permit the use of a comparatively small number of relays to give the number of message channels desired.

Other objects, purposes and characteristic features of the present invention will in part be obvious from the accompanying drawings, and in part pointed out as the description of the invention progresses.

In describing the invention in detail reference will be made to the accompanying drawings, in which:

Fig. 1A and Fig. 1B placed end to end, illustrate conventionally the equipment in the dispatcher's office of a simplified system, illustrating the apparatus for controlling the switch machines and signals at one end of a passing siding;

Fig. 1C illustrates the equipment of one way station with the apparatus conventionally shown connected to the control relays for the switch machine and signals at one end of a passing siding;

Fig. 2C illustrates the equipment of a way station showing a modification of the connections that may be used, so that a large number of message channels may be set up with comparatively few relays;

Fig. 3 illustrates in a symbolic manner the various combinations of contact positions and the message channels obtained thereby for mes-

sage channel selecting relay bank shown in Fig. 2C; and

Fig. 3A illustrates diagrammatically the symbolic showing of the combination 8² of Fig. 3.

5

Description of apparatus

Although in practice the dispatcher controls the switch machines and wayside signals of a large portion of a railway system, possibly including many passing sidings, diverging routes, draw bridges, railway crossings, and the like, the present invention has for convenience been shown as applied to the apparatus located at the west end of the passing siding PS¹ (see Fig. 1C) connecting to the main track TK¹ of a single track railway system, signalled with absolute-permissive-block signalling to the track section, preceding the track section (as shown in Fig. 1C) enclosed by the insulated joints 182. The west end of this passing siding contains the track switch TSW¹. This switch has associated therewith the usual detector track circuit insulated from the rest of the track by insulating joints 182, and included therewith the fouling section FS¹ of the passing siding PS¹ connected by wires 189 and 190 in the usual manner. This detector track circuit contains the usual track battery 191, and track relay TR¹. The starting signals for the main track and siding at the west end of the passing siding PS¹ have been designated SW¹ and SW² respectively, and the corresponding entering signals have been designated SE¹ and SE².

In the tower is preferably located a miniature track layout corresponding in every detail to the system over which the dispatcher has control, and in the particular arrangement shown includes only the passing siding PS. This miniature track layout has an indicating lamp I associated therewith, which if illuminated indicates the occupancy of the corresponding detector track circuit, namely, the detector track circuit containing the track relay TR¹. The track switch TSW¹ at the west end of the passing siding PS¹ is preferably controlled by a switch machine SM¹, which switch machine is preferably controlled by the switch machine relay SMR¹, which relay is in turn controlled by the lever SML through the medium of the self stepping synchronous selector system hereinafter described. Similarly, the signals SE¹, SE², SW¹ and SW² are controlled by the signal relay SR¹ and the direction relay DR¹ through the medium of the synchronous selector system in accordance with the position of the lever SL located in the dispatcher's office.

With the drawings, Fig. 1A and Fig. 1B placed end to end, we have an illustration of the dispatcher's office, having a bank of message channel selecting relays 1 to 17 inclusive, which are controlled through a line relay L⁰, by alternate positive and negative impulses set up by a master relay MR, and two time spacing repeater relays S¹ and S². The master relay MR and its spacer relays S¹ and S² are interconnected to produce a non-mechanical rotation, which results in a positive or a negative impulse being placed on a stepping wire 281 when the relay MR is in its corresponding energized position. The operation, of this impulse generating group of relays, is controlled directly by a control repeating relay CRR¹ which is in turn controlled by a control relay CR and an initiation relay IN, which is initiated either by a movement of a control lever such as SL or SML, or by connecting a message wire 202 with a common wire 200 while the system is at rest.

The dispatcher's office equipment is connected to a way station equipment or equipments such as illustrated in Fig. 1C by three line wires consisting of a common wire 200, a stepping wire 201, and a message wire 202. The way station as illustrated in Fig. 1C has a line relay L¹ connected in series in the stepping wire 201 and with the line relay L⁰ in the dispatcher's office. The line relay L¹ controls its bank of channel selecting relays 1¹ to 7¹ inclusive. It is obvious that the operation of the channel selecting relays 1¹ to 7¹ in the way station will be in synchronism with the channel selecting relays 1 to 17 in the dispatcher's office, due to the fact that the line relays L¹ and L⁰ are connected in series and by reason of the similarity of their circuit connections. With the system initiated and the relays 1 to 17 inclusive being operated sequentially and in synchronism with the relays 1¹ to 7¹ inclusive, a control, or other indications may be sent, or received, over a predetermined message channel, which occurs at a predetermined time in the operation cycle of the sequentially operated message channel selecting relays.

For convenience in explanation of the circuits and relays involved therein, the relays of the same type have been given characteristic letters having the individual relays distinguished by suitable exponents, with each type of relay having the characteristic features as briefly summarized below, with any variations to meet a specific case, mentioned where that specific example is set forth.

(1) The relays 1 to 17 inclusive, Figs. 1A and 1B, the relays 1¹ to 7¹ inclusive, Fig. 1C, and the relays A, B, C and D, and X, Y, and Z, Fig. 2C, used to produce the non-mechanical rotation by successive relay movements, are of the polar permanent magnet stick type. In other words, when an energy impulse of a certain polarity has been applied, and has moved its contacts to the position determined by the polarity, a permanent magnet incorporated within the relay holds the armature in that position. The OS relay and the relays S¹ and S² are also of the polar stick type.

(2) The line relays L⁰ and L¹ are polar, biased to neutral, type relays, which respond in such a manner that their contacts are held in neutral or non-contact-making positions during the time that no energy is applied, but are moved either to the right or to the left as positive or negative impulses, respectively, are applied.

(3) The relays ST⁰, ST¹ etc. are neutral relays, having the characteristic feature that they do not pick up upon application of impulses, which are of the normal rate, sent over the stepping circuit; but upon application of a long impulse their armatures are picked up within a predetermined period of time, which period of time is a predetermined fractional part of the total duration of the long impulse.

(4) The relays IN, IN¹ etc. are neutral relays, which may be either quick or slow acting during their release period, as the necessity of a specific case demands.

(5) The relay CR is a neutral relay with two windings, so designed that the armature will pick up with a certain normal value of current flowing in either winding.

It will be stated here, that each polar relay is considered to assume a right hand or positive position, with an application of positive potential to the left hand terminal of the relay, and to assume a left hand or negative position, with an application of negative potential to the left hand

terminal of the relay. It is also assumed that the normal positions of all relays are their present full line positions, so that when a relay is spoken of as being in a reverse or abnormal position, it shall mean the dotted position as shown in the accompanying drawings.

The levers 18, 19, and 20 are connected together mechanically, as are also the levers 21 and 22, so that the movement of the controlling handles SL or SML, respectively, will move the inter-connected levers together. It will be observed, that the levers 18 and 21 make contact with the common wire at points 186 but momentarily, as the levers are moved to their dotted line 15 positions.

It is believed that the features of the system will be better understood by considering its operation.

Operation

20 The apparatus and circuit arrangement embodying the present invention may be divided into two distinct groups, as follows: (1) The stepping, or synchronizing circuit arrangements and mechanisms which have a major function in producing a non-mechanical rotation by successive relay movements occurring in exact synchronism, and which provides that the system shall be normally at rest, but shall be initiated for synchronous rotation of relay movements, either, 25 when the dispatcher operates a lever to control a distant function, or when an OS indication is present at a waystation ready for transmission to the dispatcher's office, and to be stopped at the end of the second cycle if there are no further indications to be transmitted; (2) a message channel circuit arrangement and mechanisms, which have a major function of utilizing the non-mechanical rotation of successive relay movements in producing temporary message channel circuits, 30 which are completed during the period of time intervening between the final movement of one relay and the initial movement of the next relay in succession, which message channel circuits are to be used for transmitting impulses either for 35 OS indications or for controlling switch machines, way side signals, de-rails and the like.

Operation of the synchronizing circuits

50 As has been explained, the line relays L⁰ and L¹ are energized by the impulses which are impressed on the stepping wire 201. These line relays serve to repeat for the local circuits, the impulses passed over the stepping wire, so that the message channel selecting relay banks may be synchronously operated.

55 These message channel selecting relays are of the polar stick type, which have the required number of contacts to meet the needs in a specific location in the circuits. The first two of these contacts are "break and make" beyond center, for use in the operating circuits of the relays. In other words, the circuit for operating each relay, is carried through one of two of its own contacts, so that one contact must break and make beyond center, when the contacts are moved in one direction, and the other contact make and break beyond center when the contacts are moved in the other direction. This is to insure 60 that no relay shall become stuck on center.

70 The message channel selecting bank of relays is so organized, that the movement of one relay to a given position, opens its own circuit and closes the circuit for the next relay to be operated. This means that the polarity of successive

75 relays must be alternated, so that an impulse, which operates a given relay, will not operate the next relay in succession, when its circuit is closed, but rather must require an impulse of the opposite polarity. With this organization of apparatus every impulse produces a definite predetermined result, which as applied to the banks of relays as shown in Figs. 1A, 1B and 1C, determines 80 that the number of relays in the banks shall be an odd number, so that every impulse shall 85 be an active one.

The relays 1 to 17 inclusive, and the relays 1¹ to 7¹ inclusive, operate in identical fashion, such that impulses alternately negative and positive, placed on the wire 224, connected to the contact 32 of relay 1 (see Figs. 1A and 1B) and the wire 228 connected to the contact 108 of relay 1¹, (see Fig. 1C) energize the successive relays in succession to reverse positions. Also, impulses, alternately positive and negative, placed on the wire 226 connected to contact 33 of relay 1, and on the wire 229 connected to the contact 109 of relay 1¹, energize the successive relays in succession to their normal positions. Thus, the circuit arrangement is so organized that relay 1 moves 25 its contacts to a negative position with a negative impulse, relay 2 moves its contacts to a positive position with a positive impulse, and relay 3 moves its contacts to a negative position with a negative impulse, and in like manner all relays operate 30 to a reverse position.

More specifically it will be stated, that alternate negative and positive impulses applied to the stepping wire 201, are repeated by the relay L⁰ in such a manner that alternate negative and positive impulses are placed upon wire 226 receiving energy from battery 187 and 188 through contact 104. These impulses are routed, so to speak, through the wire 228 to the contact 109 of relay 17. This contact directs the impulses 40 on either wire 224 or wire 226, according to its position.

Let us assume, that a negative impulse is placed on the wire 224. This impulse passes through positive contact 32, through relay 1, to common, 45 thus moving its contacts to a negative position. Should that negative impulse on the wire 224 continue after the relay 1 has moved its contacts to the negative position, that impulse would be applied to relay 2, through its negative contact 35, but since relay 2 is already in the negative position, the negative impulse will not effect its movement. However, the positive impulse which is next placed on wire 224 flows through negative contact 32 and negative contact 35, through relay 50 2, which moves its contacts to a positive position. Should that positive impulse continue after the relay 2 has moved its contacts to a positive position, that impulse would be applied to relay 3 through positive contact 39, but as relay 3 is in 55 a positive position it does not affect movement thereof. The negative impulse next placed on wire 224 flows through this circuit in such a manner as to move the contacts of relay 3 to a negative position, and in like manner as positive 60 and negative impulses are placed on the wire 224, the relays in the bank are successively moved from their normal full line position, to their reverse dotted line positions, until the last relay 65 of the group has been reversed.

70 Now let us assume that a positive impulse is placed on wire 226, as would occur in practice while the relay 17 assumes its left-hand position. This positive impulse will flow through negative contact 33 of relay 1, through relay 1 to common, 75

and return relay 1 to its normal position. The movement of relay 1 to a positive position, sets up the circuit for relay 2 through positive contact 36. But relay 2 is at this time in a positive position and does not respond to that positive impulse even if it should be indefinitely prolonged. However, the next successive impulse, which is negative, moves the contacts of relay 2 to a negative position, thus setting up the circuit for relay 3. 10 In like manner, the relays 1 to 16 inclusive are returned to their normal positions.

The relays 1 to 17, as shown in the drawings, Figs. 1A and 1B, are assumed to have been reversed and relays 1 to 16 to have been returned 15 to their normal positions thus leaving the circuits as shown in the drawings. With such a condition obtaining, a circuit is made up for the positive and negative impulses repeated at contact 194, as follows:—through wire 228 negative contact 108, wire 226, positive contact 33, negative contact 36, positive contact 40, negative contact 44, positive contact 48, negative contact 52, positive contact 56, negative contact 60, positive contact 64, negative contact 68, positive contact 72, negative contact 76, positive contact 80, negative contact 84, positive contact 88, negative contact 94, negative contact 99, wire 227, through relay ST⁰ to common. As has been explained heretofore the relay ST⁰ does not pick up upon 30 the impulses of the normal stepping rate, so that the relays must stop at the end of each cycle, because no release can be obtained at the end of the cycle of a relay bank until the corresponding relay ST⁰ or ST¹ has been picked up.

35 It will be noted here, that it is desirable that the system shall go through at least two cycles after it has been initiated, and then cease operation providing that all OS indications have been received. In order to accomplish this, the circuits of relays IN and CR are so arranged, that when the relay IN is energized the relay CR is energized. This means that, as the system is approaching the end of a cycle, the stick circuit of the relay CR must be opened preceding the 40 opening of the stick circuit of the relay IN, so that the relay CR will not drop, as will the relay IN at completion of the first cycle, but will drop at the end of the second cycle. To do this, the contact 97 has connected in parallel with it the contact 194, in such a manner, that the resulting combination of the two contacts is such, that the stick circuit of the relay IN is completed through either contact 97 or contact 194, except during the period of time that exists after 45 the initiation of contact 97 toward its normal position, and the time that the contact 194 again assumes a reverse position. This may be explained by saying that, with the relays 16 and 50 17 with their contacts in the present normal positions, contact will be made, when contact 194 is moved to a positive position, so that wire 218 is then connected to common wire 200, through wire 221 and positive contact 194, but when normal contact 97 is reversed, the wire 218, is connected to the common wire 200, through positive contact 97. Then, with the next relay movement, which is the movement of the contacts of relay 55 17 to a negative position, the circuit from wire 218, through positive contact 97, to the common wire 200 is still made, although broken at contact 194. However, on the next half cycle when the relays return to their normal position, the circuit through positive contact 97, is broken, and 60 is not again made until the contact 194 returns

to a positive position. Thus, it is seen that the circuit under consideration is broken only at one time, which time is at the end of each cycle completed by the message channel selecting bank of relays 1 to 17 inclusive.

5 In the same manner, the stick circuit for the relay CR has the contact 87 connected in parallel with contact 92, which thus accomplishes the same result, as the contacts 97 and 194 connected in parallel accomplish for the stick circuit of relay IN. The stick circuit of the relay CR is momentarily open during a period of time preceding that period during which the stick circuit of relay IN is open. It will now be seen that upon nearing the completion of the first cycle of the non-mechanical rotation, as the relay 14 has returned its contacts to the normal position, the stick circuit for the relay CR is broken, but the relay CR does not drop due to the fact that the current for the relay IN flows through its upper winding. Upon movement of the contacts of relay 15 to their normal position, the stick circuit for the relay CR is again closed, and the stick circuit for the relay IN is opened upon movement of the contacts of relay 16 to their normal position, which immediately drops the relay IN. The relay IN remains de-energized due to the dropping of its front stick contact 23. As the rotation of the message channel selecting bank of relays nears 10 the completion of its second cycle, the stick circuit for the relay CR is again opened, and the relay CR drops due to the fact that the relay IN has formerly been de-energized.

15 The control relay CR, as its name implies, controls the initiation and stopping of the impulse generating group composed of relays MR, S¹ and S². But in order that the starting condition may be fulfilled, namely, a long positive impulse to pick up the relay ST⁰ and ST¹ etc., a 20 control repeating relay CRR is interposed in the control, to produce the long positive impulse upon the stepping wire 201.

25 During the period of time which exists after the relay CR has been energized, and before the 40 relay CRR picks up, there is a circuit completed which places positive potential upon the relay MR. Thus, a positive impulse is placed upon the stepping wire 201. This positive impulse is maintained until the relay ST⁰ has picked up and the relay 17 has moved its contacts to a positive position, thus closing a circuit for picking up the relay CRR. The picking up of relay CRR re-routes the stick circuit of the relay IN through the front contact 195 to the wire 218, which is 30 connected, at this time, to the common wire 200. Also, the relay CRR must be slightly slow releasing, sufficiently to prevent the back contact 195 to make, before the front contacts 23 and 197 of the relay IN break. Failure to do this 35 would cause the system to continue operation after the end of the second cycle.

40 The picking up of the relay CRR cuts off the positive potential applied to the relay MR, through back contact 105, and closes front contact 106. The closing of contact 106, gives a potential to the relay MR as determined by the position of relay S². The long positive potential on relay MR moved its contacts to a positive position, which energized the contacts of relay S¹ to a positive position, which, with said contacts of relay S¹ in such a position, energizes the contacts of relay S² to a negative position, thus placing negative potential on the relay MR when front contact 106 of relay CRR is closed. With 45 50 55 60 65 70 75 70 75

negative potential on relay MR, its contacts assume a negative position, which energizes the relay S¹ to move its contacts to a negative position, which in turn energizes the relay S² to move its contacts to a positive position, placing positive potential on the relay MR. Thus we have shown how the successive operation of the relays MR, S¹ and S² occur, to produce alternate positive and negative impulses used for stepping.

10 It will be noted here that the time interval of these impulses is determined by the operating time of the relays included within the impulse generating group. Also, it is seen that this group can not get ahead of the line relays, as the relay 15 S¹ is in series with said line relays.

We will now assume that all the apparatus in the dispatcher's office and in the way station (as illustrated in Figs. 1A, 1B and 1C, placed end to end) to be at rest. To illustrate the starting of 20 the apparatus, the revolving of the message channel selecting relays in a non-mechanical rotation, to illustrate how the alternate positive and negative impulses are produced by the impulse generating group, operating in a non-mechanical 25 rotation, and to show the results of the movement of a control lever, we will assume that the dispatcher desires to move the switch TSW¹ from the normal position to a reverse position routing the east bound main-line traffic onto the 30 passing siding PS¹.

The movement of the track switch TSW¹, is controlled by the switch machine SM¹ associated therewith, which is in turn controlled by the switch machine relay SMR¹. With the polar 35 contact of the relay SMR¹ in a right hand or positive position, the switch machine operates so that the switch TSW¹ assumes a normal position allowing east bound traffic to proceed upon the main track, and with the polar contact of 40 relay SMR¹ in a negative or left hand position the switch machine SM¹ operates to move the track switch TSW¹ to a reverse position allowing the east bound traffic to proceed onto the passing siding PS¹. The position of the polar 45 contacts of the relay SMR¹, is determined by the position of lever SML by means of a control impulse transmitted to the relay SMR¹ through the medium of the synchronous selector system hereinafter described.

50 We will now assume that the dispatcher moves the lever SML to a negative position. During the movement of this lever to a negative position, the lever 21 makes momentary contact 188 which sets up a circuit as follows:—from positive battery 55 183, through wires 203, 217, 216, and 215, through the upper winding of relay CR wire 214, relay IN, wire 213, lever 21, contact 189, to the common wire 200. This momentary circuit energizes the relays IN and CR, in as much as the current that 60 flows in this circuit passes through the upper winding of the relay CR and the winding of relay IN connected in series. These relays CR and IN are held energized through stick circuits completed by their front contacts 24 and 23 respectively. The stick circuit for the relay IN may be traced as follows:—positive battery from battery 65 183, through wires 203, 217, 216, 215, relay CR, wire 214, relay IN, wire 229, front contact 23, wire 193, back contact 195, to the common wire 200. The stick circuit for the relay CR may be traced as follows:—positive battery from the battery 70 183, wire 203, 217, 218, and 215, lower winding of relay CR, front contact 24, wire 219, positive contact 92, to the common wire 200.

75 The energization of the relay CR causes posi-

tive potential to be applied to the relay MR through a circuit traced, as follows:—positive battery from the battery 183, wires 203, 217, 216, 224, 225, negative contact 102, wire 226, back contact 105, wire 227, front contact 26, wire 278, through the relay MR to the common wire 200. This positive potential applied to relay MR moves contacts 27 and 28 to a positive position. With contact 27 in a positive position a circuit is set up as follows:—positive battery from battery 183, 10 through wires 207, positive contact 27, wire 279, relay S¹, wire 281, relay L⁰, wire 201, relay L¹, to the common wire 200. With this circuit closed, current flows through the windings of relays L⁰ and L¹ to move their contacts to a positive position. 15

With the contact 104 of relay L⁰ in a positive position, positive potential is placed on the relay ST⁰ through a circuit traced as follows:—positive battery from battery 187, through wire 228, negative contact 108 of relay 17, wire 226, positive contact 33 of relay 1, negative contact 36 of relay 2, positive contact 40 of relay 3, negative contact 44, positive contact 48, negative contact 52, positive contact 56, negative contact 60, positive contact 64, negative contact 68, positive contact 72, negative contact 76, positive contact 80, negative contact 84, positive contact 88, negative contact 94, negative contact 99, wire 227, through the relay 30 ST⁰ to common. During the time that the contact 104 of relay L⁰ is in a positive position this circuit is maintained so that the relay ST⁰ will pick up in a predetermined length of time, which is slightly greater than the pick up time of relay ST¹. 35

At the same time that the relay ST⁰ is picking up due to the positive potential being placed upon it, the relay ST¹ is being picked up through a circuit traced as follows:—positive battery from battery 198, positive contact 181, wire 230, negative contact 134, wire 229, positive contact 109 of relay 11, negative contact 113 of relay 21, positive contact 117 of relay 31, negative contact 121 of relay 41, positive contact 125 of relay 51, negative contact 129 of relay 61, negative contact 133 of relay 71, through the relay ST¹ to common. As the relay ST¹ requires less time to pick up than the relay ST⁰, said relay ST¹ will close its front contact 136, allowing positive potential flowing from the battery 192 through the circuit just traced for relay ST¹ to be also placed upon the relay 71 through front contact 136, wire 231, through relay 71 to common, thus energizing the relay 71, so that its contacts move to a positive position. Similarly, the relays of the type ST in all other way stations of such a system will pick up and allow the last relay of the message channel selecting group over which they control, to be energized to a positive position. 55

As soon as the relay ST⁰ picks up its front contact 103, a circuit is completed so that positive potential from the battery 187 flows through the circuit heretofore traced for the relay ST⁰, being shunted from the relay ST⁰ through the 65 front contact 103, wire 280, through relay 17 to common. Thus the contacts of relay 17 are moved to a positive position.

The movement of the contacts of relay 17 to a positive position, opens the circuit (heretofore 70 traced) at the contact 102 of relay 17, for placing the positive potential on the relay MR. Also, as soon as the contacts of relay 17 assume positive position a circuit is completed which energizes the relay CRR through the circuit traced as fol- 75

lows:—positive battery from battery 183, through wire 203, 217, 222, front contact 25, wire 223, to relay CRR, wire 218, and 221, positive contact 194 of relay 17, to the common wire 200.

5 With the relay CRR energized, its front contact 106 closes a circuit, which permits a potential of a polarity as determined by the position of contact 29 of relay S² to be placed upon the relay MR. The relay MR having been previously energized with a positive potential, causes the contacts of relay S¹ to assume a positive position through a circuit heretofore traced. With the contact 30 of relay S¹ in a positive position a negative potential is placed upon the relay S² through a circuit traced as follows:—from the negative battery 184, through wires 208, 209 and 210, positive contact 30, wire 211, through the relay S² to the common wire 200. Thus the contact 29 of relay S² is energized to a negative position. When the relay CRR is energized, and its front contact 106 is closed, the potential placed upon the relay MR is negative and flows through a circuit traced as follows:—from negative battery 184, wires 208 and 209, negative contact 29, wire 206, front contact 106 of relay CRR, wire 278, through the relay MR to the common wire 200. This negative potential placed upon the relay MR causes its contacts to be moved to a negative position, causing the result that a negative potential is placed upon the relays S¹, L⁰ and L¹ in series through a circuit traced as follows:—from negative battery 184, through wire 212, negative contact 27, wire 279, relay S¹, wire 201, relay L⁰, wire 201, relay L¹, to the common wire 200.

The energization of relay CRR, also re-routes the stick circuit of the relay IN through a circuit traced as follows:—positive battery from the battery 183, through wires 203, 217, 216 and 40 215, relay CR, wire 214, relay IN, wire 220, front contact 23, wire 196, front contact 195, wire 261, front contact 197, wire 260, and 218 and 221, positive contact 194 of relay 17 to the common wire 200.

45 With a negative potential on the relay MR due to the energization of the relay CRR, a negative potential is placed upon the relays S¹, L⁰ and L¹ which moves their contacts to a negative position. With the contact 104 of relay L⁰ in a negative position a circuit is set up which places negative potential on the relay 1, being traced as follows:—from the negative battery 188, through negative contact 104, wire 228, positive contact 100 of relay 17, wire 224, positive contact 55 32 of relay 1, through the relay 1 to common, thus energizing the relay 1 to move its contacts to a negative position. At the same time the contact 107 of relay L¹ is in a negative position, which places negative potential upon the relay 1¹ through a circuit traced as follows:—from negative battery 199, through negative contact 107, wire 230, positive contact 134, wire 228, positive contact 108, through the relay 1¹ to the common wire 200. The relay 1¹ is thus energized to move its contacts to a negative position. Also, at the same time, the contact 30, of relay S¹ is in a negative position which completes a circuit to place positive potential on the relay S², with the circuit being traced as follows:—70 from the positive battery 183, through wires 203 and 204, negative contact 30, wire 211, through relay S² to the common wire 200. Thus the contact 29 of relay S² is caused to move to a positive position which results in a positive potential being placed upon the relay MR through a circuit

traced as follows:—from the positive battery 183, through wires 203, 204, and 205, positive contact 29, wire 206, front contact 106 of relay CRR, wire 278, through the relay MR to common. Thus, the contact 27 of relay MR is moved to a positive position, placing a positive potential upon the relays S¹, L⁰ and L¹, through a circuit as heretofore traced.

It will be here pointed out that as the relays S¹, L¹ and L⁰ are in series they will operate at the same time, provided that they are built with the same operating characteristics. This being so, the relay S² will operate its contacts at the same time that any message channel selecting relay operates its contacts, thus causing the result that as soon as a message channel selecting relay has been energized in the dispatcher's office and corresponding message channel selecting relay has been energized at each way station simultaneously with the energization of the relay S², then the relay MR is energized to an opposite position. Thus in like manner the impulse generating group of relays composed of relays MR, S¹ and S² proceed to operate in a non-mechanical rotation until their circuit is again opened at the contact 105 of relay CRR.

The next impulse which is produced by the relay MR, is repeated by the line relays L⁰ and L¹. As the last impulse was negative and moved the contacts of relays 1 and 1¹ to a negative position, then the next impulse is positive and is repeated by the relay L⁰ in the dispatcher's office, which establishes a circuit traced as follows:—positive battery 197, through positive contact 104, wire 228, positive contact 100, wire 224, negative contact 32, negative contact 35, through the relay 2, to the common wire. Thus the contacts of relay 2 are energized to the positive position. Likewise the positive impulse repeated by the relay L¹ in the way station shown in Fig. 1C flows through a circuit traced as follows:—from positive battery 198, through positive contact 107, wire 230, positive contact 134, wire 228, negative contact 108, negative contact 112, through the relay 2¹, to the common wire. Thus the contacts of relay 2¹ are moved to a positive position.

With the relays 2 and 2¹ in positive positions a circuit is set up during a central portion of the total channel time, as explained hereinafter which allows negative potential to be placed on the relay SMR¹, being traced as follows:—from the negative battery 184 through wires 200, 233, lever 22 in a left hand position, wire 235, positive contact 31, of relay 2, positive contact 41 of relay 3, negative contact 45 of relay 4, positive contact 49, negative contact 53, positive contact 51, negative contact 61, positive contact 65, negative contact 69, positive contact 73, negative contact 77, positive contact 81, negative contact 85, positive contact 90, negative contact 95, positive contact 101, through wire 232, positive contact 31, wire 236, negative contact 28, wire 202, to the way station, wire 241, positive contact 135, negative contact 130, positive contact 126, negative contact 122, positive contact 118, positive contact 114, through the relay SMR¹ to the common wire 200. Thus the polar contact of relay SMR¹ is moved to a negative position effecting a control of switch machine, which in turn moves the switch TSW to a reverse position routing the east bound traffic onto the passing siding PS.

The succeeding negative and positive impulses sequentially operate the relays 3, 4, 5, 6, 7, 8, 9, 75

10, 11, 12, 13, and 14 to their respective reverse positions, in a similar manner as explained for relays 1 and 2. When the contacts of relay 14 assume a reverse position, the contact 87 completes a circuit in parallel with contact 92, so that the next impulse which is negative and moves the contacts of relay 15 to a reverse position, does not open the stick circuit of relay CR. Likewise the next positive impulse which energizes the contacts of relay 16 to a reverse position, moves contact 97 to a reverse position which completes a circuit in parallel with contact 194, so that although the circuit through the contact 194 of relay 17 is broken upon the application 15 of the next negative impulse, the stick circuit for the relay IN, and the energizing circuit for the relay CRR is still maintained. Now that the relays 1 to 17 inclusive, have gone through one-half their cycle, the contacts of relay 17 are then 20 in a negative position, which routes the stepping impulses through the wire 226 instead of wire 224, so that the relays 1 to 16 may be returned to their normal positions, and it is assumed that they are so returned. During this second half 25 cycle, these relays are returned to their normal position sequentially, and when the relay 14 returns to its normal position the stick circuit for the relay CR was opened and again closed upon movement of relay 15 to a normal position, but 30 did not drop relay CR, due to the fact, that the current for relay IN was flowing through the upper winding of relay CR. With the relays 1 to 16 in their normal positions, the circuit for picking up the relay ST⁰ is completed, and also 35 the circuit including the relays CRR and IN in multiple is opened, thus dropping both the relays CRR and IN. The dropping of relay CRR closes the circuit for placing a positive potential upon relay MR through the front contact 26 of relay CR and back contact 105 of relay CRR. Thus in due time, the relay ST⁰ again picks up 40 and the relay 17 is energized to the positive position, which again picks up the relay CRR, causing the generation of positive and negative impulses by the impulse generating relay group S¹, S², MR, which impulses are applied to the stepping wire 201. The channel selecting relays complete another cycle during which time the relay CR, is deenergized by the movement 45 of contact 87 of relay 14 to a normal position, which is possible inasmuch as the relay IN is now deenergized. The dropping of relay CR also in turn drops the relay CRR, which has a slow releasing period to an extent that the impulse generating group will produce at least two impulses after the stick circuit of relay CR has been completed. Thus two cycles of operation have been 50 completed.

The operation of the control circuits for the 55 relays 1 to 7¹ inclusive and the relay ST¹ is identical to that explained for the relays 1 to 17 inclusive and the relay ST⁰.

Let us now consider the synchronous operation 60 of the message channel selecting bank of relays in the dispatcher's office, in regard to their co-operation with a message channel selecting bank of relays at a way station such as shown in Fig. 1C. As the long positive starting impulse picked up the relays ST⁰ and ST¹, and the relays 65 17 and 7¹ are energized to a positive position, the first negative impulse energizes relays 1 and 1¹ to a negative position. Likewise the next succeeding positive impulse energized relays 2 and 2¹ to a positive position, with each succeeding 70 impulse energizing its respective corresponding

relay, until relays 7 and 7¹ have been energized to a negative position. The next succeeding impulse is a positive impulse which energizes relay 8 to a positive position and relay 1¹ to a positive position. Likewise the succeeding negative 75 impulse energizes relay 9 to a negative position, and relay 2¹ to a negative position, until relay 13 has been energized to a negative position and the relay 6¹ has been energized to a negative position. The following impulses which are used 10 in the dispatcher's office to complete the cycle in the relays 1 to 17 inclusive are absorbed at the way station in the relay ST¹ without producing any relay operation. So it is easily seen that should the way station relays for any reason 15 whatsoever, such as extraneous foreign impulses, or lack of immediate response of a relay, be out of step, that these extra impulses generated at the dispatcher's office, would bring the way station up to the end of the cycle. Thus, at the 20 end of each cycle, the relays at the dispatcher's office and the relays at the way station are again synchronized.

It will be stated here that should the lever 25 SL be moved to either of its extreme positions, the system would be initiated and impulses of a polarity corresponding to the positions of the levers 19 and 20 would be sent over their corresponding message channels, which are set up at a suitable time during the sequential operation 30 of the message channel selecting relays, while they are completing one cycle. Let us assume that the lever SL is in the right hand position, moving the lever contact 19 and 20 to a right hand position which clears the signal 35 SE¹ allowing traffic to proceed in an east bound direction. The message channel for lever contact 19, assuming that the message channel selecting relays have been stepped to their proper 40 positions, may be traced as follows:—positive 45 battery from battery 183, through wires 203, 217, 216, 224 and 234, lever 19 in a right hand position, wire 238, negative contact 34, negative contact 37, positive contact 41, negative contact 45, positive contact 49, negative contact 53, positive 50 contact 57, negative contact 61, positive contact 65, negative contact 69, positive contact 73, negative contact 77, positive contact 81, negative contact 85, positive contact 90, negative contact 95, positive contact 101, wire 232, negative contact 31, wire 237, positive contact 28, wire 202, to the way station shown in Fig. 1C, wire 241, positive contact 135, negative contact 139, positive contact 126, negative contact 122, positive 55 contact 118, negative contact 114, negative contact 110, through the relay SR¹ to the common wire 200. Thus the relay SR¹ is energized with positive potential which causes its polar contact to assume a positive position as shown. The message channel for the lever contact 20, assuming that the message channel selecting relays have been stepped to proper positions, may 60 be traced as follows:—positive battery from battery 183, through wires 203, 217, 216, 224 and 234, positive lever 20, wire 290, negative contact 41, 65 negative contact 45, positive contact 49, negative contact 53, positive contact 57, negative contact 61, positive contact 65, negative contact 69, positive contact 73, negative contact 77, positive contact 81, negative contact 85, positive contact 90, 70 negative contact 95, positive contact 101, wire 232, negative contact 31, wire 237, positive contact 28, wire 202, to the way station shown in Fig. 1C, wire 241, positive contact 135, negative contact 139, positive contact 126, negative contact 75

122, negative contact 118, through the relay DR¹ to the common wire 200. Thus the relay DR¹ is energized with positive potential causing its polar contact to be moved to a positive position.

5 Let us again assume that the system is at rest, and that a train enters the track section TK¹. The occupancy of track section TK¹ shunts the track relay TR¹, so that its contacts 139 and 138 assume a de-energized position. As the contact 138 is a make before break contact, a circuit is momentarily completed from the battery 280 through contact 139 and the relay IN¹ to the common wire 200. This momentary circuit energizes the relay IN¹ which is a slow releasing relay, 15 having a release period sufficient to allow the system to complete one cycle before it is entirely de-energized. As the system is at rest, and the relay IN¹ is energized, a circuit is completed through the contact 137 of relay IN¹ 20 which will initiate the system and is traced as follows:—from the positive terminal of battery 183, through wires 203, 217, 216 and 215, upper winding of relay CR, wire 214, relay IN, wire 239, negative contact 92 of relay 16, negative contact 193 of relay 17, wire 202, to the way station shown in Fig. 1C, wire 241, negative contact 135, negative contact 131, wire 249, front contact 137 of relay IN¹, to the common wire 200. Thus a current flows through the upper 30 winding of relay CR and the winding IN moving the contacts to an energized position, thus initiating the system and stepping the message channel selecting relays in sequential operation for completing two cycles for reasons heretofore 35 explained. When the message channel selecting relays assume proper positions, which occurs once during each of the two cycles, a message channel is set up so that the OS indication, telling the dispatcher that the track section TK¹ is 40 occupied, may be transmitted. This message channel is traced as follows:—negative battery from battery 280, through back contact 139, wire 281, positive contact 122, positive contact 126, negative contact 130, positive contact 135, wire 45 241, wire 202, to the dispatcher's office shown in Figs. 1A and 1B, to the negative contact 28, wire 236, positive contact 31, wire 232, positive contact 161, negative contact 95, positive contact 96, negative contact 85, positive contact 81, negative contact 77, positive contact 73, negative contact 69, positive contact 65, negative contact 61, positive contact 57, negative contact 53, positive contact 49, positive contact 45, wire 282, through the relay OS to the common wire 200. Thus the 50 55 polar contact 185 of the relay OS is energized to a negative position illuminating the indicator lamp I, giving indication to the dispatcher that the track section TK¹ is occupied.

It will be noted here, that the number of relays 60 in the dispatcher's office was arranged for use with the modified way station as shown in Fig. 2C. Thus, there is an excessive number of synchronizing impulses which are not practicable for the type of way station connections as shown 65 in Fig. 1C.

When way stations, such as shown in Fig. 1C, are used in series, provisions must be made that each way station of this type must have an equal 70 number of relays, which give the total required number of message channels. This is necessary, since, as soon as any one way station comes to the "at rest" period, this station then has a message channel set up which is used for initiation. Should an OS indication occur at this particular 75

station, then the message wire 202 would be connected to the common wire 200 at this particular station, which condition would result in the extermination of any control indications which might be sent over the message wire for use at some other way station, and for this reason it should be understood that all way station relay banks of a particular system should have the same number of channel selecting relays. 10

Operation of message channel circuits

After having explained the synchronous operation of the channel selecting relays, we may now consider how contacts on corresponding relays 15 in the two relay groups close synchronously to complete a plurality of sequentially closed message circuits. These sequentially closed circuits may be conveniently termed message channels, and the period of time during which they are 20 closed, may be suitably termed total channel time.

It is possible, due to slight variations in characteristic operating time of the channel selecting relays for an overlapping of the total channel times to occur, which might cause an indication intended for one message channel to be indicated on two message channels. In eliminating this possibility, a circuit is provided which 25 splits the total channel time into three periods 30 and permits the indication to be passed into its own channel, only during the central period of the total channel time.

In a system, as shown in Figs. 1A, 1B and 1C, 35 this total channel time is divided into three periods by the relays MR, S¹ and S². The message wire is connected through the movable contact 28, of relay MR, so that a circuit may be completed through positive or negative contact 28 to wires 237 and 236 respectively, through negative or positive contacts 31 respectively, to wire 232, which is then carried to the message channel selecting relay to be connected to the various message channels. 40

By way of illustration, we will assume that the 45 operating time of relays MR, S¹ and S² are of equal length and equal to the operating time of a channel selecting relay such as relay 1. Then relay S¹ being in series with the relays L⁰ and L¹ will operate during the same period of time as 50 the line relays, also the relay S² will operate during the same period of time as the particular message channel selecting relay which is then being operated will operate. Also, we will assume that the system has been initiated and the 55 contacts 27 and 28 of relay MR have been moved to a positive position by a positive potential being applied to the relay MR. This position of contacts 27 and 28 energizes the relay S¹ to a positive position as shown, but at this time the 60 message circuit is broken at contact 31. With the contacts of relay S¹ energized in a positive position the contact 29 of relay S² is energized in a negative position as shown. It will be remembered that the channel selecting relay 65 operates at the same time as the relay S², so that we may assume, that as soon as the contact 29 has reached a negative position, the period of time representing the total channel time has begun. With contact 29 in a negative position, 70 the contacts of relay MR are energized to a negative position, at which time the message circuit is continuous from the message wire 202 through negative contact 28, wire 236, positive contact 31, to wire 232, to any particular mes- 75

sage channel. It is seen that a period of time has elapsed since the beginning of the total channel time, and the instant that the contact 28 arrived in a negative position. The movement 5 of contacts 27, 28 to a negative position energizes the relay S¹ to move the contacts 30 and 31 to a negative position. At the initiation of the movement of contact 31, the message circuit heretofore traced is broken, but the total channel 10 time has not elapsed until the contact 29 of relay S² has been initiated in movement toward a positive position by the application of a positive potential to the relay S¹. Hence it is seen, that the message circuit is closed only during the period 15 of time that it takes the current to build up sufficiently in the winding of relay S¹ to initiate movement of its contacts, thus making it possible to regulate the indication or message time by increasing the characteristic operating time of 20 relay S¹.

It will of course be understood that to apply this same principle of sending the message or indication during a time which is central in respect to the total channel time, to a way station 25 where the stepping impulses are not repeated by a line relay, as in Fig. 2C, the stepping impulses should not be repeated for the dispatcher's message channel selecting bank of relays, and the contact 31 should be controlled by 30 relay S² instead of relay S¹.

The contacts of successive relays which close and open the message channels, are normally in alternate positive and negative positions, so that there is only one time that two successive 35 contacts are in like positions. This may be illustrated by the relays 1 and 2. The message contacts 33 and 34 are in a positive position, the message contacts 37 and 38 are in a negative position and the message contacts 41 and 42 are 40 in a positive position etc. When the contact 34 moves to a negative position, it is in a corresponding position with the contact 37 until the relay 2 is energized moving its contacts to a positive position, at which time the contact 37 45 is in a corresponding position to contact 41. Then relay 3 is energized to a negative position and contact 41 is in a position corresponding to contact 45. Thus it is seen that since the message circuit is completed through contacts, 50 assuming corresponding polar positions of two successive relays, that the circuit is only completed from the time of operation of the first relay until the operation of the second relay of two adjacent relays in the series. This principle has been carried out in the selection of 55 all message channels.

In the instance of the dispatcher's message channel selecting relays the message wire is carried through contacts 28 and 31 assuming opposite polar positions, through the wire 232 to contact 16. With the relays 1 to 17 inclusive, in the at rest period, the third contacts of each relay 1 to 16 inclusive are connected in series. With the relays 1 to 16 in a reverse position the 60 fourth contacts of each relay are connected in series. The message wire which is connected to contact 16, of relay 17 as heretofore explained, is connected to either the third contact of relay 16 or the fourth contact of relay 16 according to 65 the position of the contacts of relay 17. Now, it will be easily seen that a circuit is set up, as soon as the relays S¹ and 17 have responded to the long positive impulse, through positive contact 16 of relay 17, through negative contact 70 75 95 of relay 16, positive contact 90 of relay 15

etc., through the third contacts of each relay in series to the contact 34 of relay 1, so that as soon as relay 1 receives its negative impulse and moves to a reverse position that a circuit is completed from the message wire 5 through the contacts as explained through wire 238 to the signal lever 19. As the lever SL is in a central position no indication is sent over the message wire. Upon movement of contact 37 of relay 2 to a positive position, the message 10 channel for lever SL has been broken, and a message channel is set up through positive contact 37 of relay 2. As we have assumed that the lever SML is assuming right hand position, we have a message channel set up through a circuit 15 heretofore traced. Thus the message channels are successively made and broken by the movement of each relay in the order that it occurs until the relay 17 is again moved to a negative position which transfers the message circuit 20 through the fourth contact of each relay 1 to 16. The fourth contact of each relay in the channel selecting group being in series, the message channels will be made and broken the same as shown heretofore for the third contacts of the relays, 25 until the system has completed the cycle.

Although the selection of message channels has been more specifically explained for the message channel selecting relays at the dispatcher's office, it is to be understood that the message 30 channels at the way station as shown in Fig. 1C are selected and controlled in the same manner. Thus, all that is necessary to have an indication sent from the dispatcher's office to a given control relay such as relay SMR¹, is to have the 35 relay at the way station connected to its corresponding control relay through contacts of the last and next operated channel selecting relay of both the dispatcher's relay bank and the way station relay bank.

As the description of the message channel arrangement has progressed thus far, it is only necessary to state that as the system is normally at rest, except when messages are to be transmitted, there is a channel at each way station 45 and at the dispatcher's office, which is made during this at rest period of time. This message channel is connected to some means at the way station, which in the case of Fig. 1C, is relay IN¹, which will connect this message channel to the common wire 200, when an OS indication is to be transmitted from that way station. The message channel at the dispatcher's office which occurs during the at rest period, is connected to the relay IN in such a manner, 50 that its ultimate connection to the common wire at the way station will result in the energization of relay IN. Thus means for initiation of the system from the way station is provided.

Modified form of way station

In Fig. 2C, there is shown a modified organization of connections for the message channel selecting relays, which will give more message channels per number of relays used, than will the connections as shown in Fig. 1C. It will also be noted that the stepping line impulses are not shown as being repeated by a line relay, which is an optional requirement and does not effect the synchronous operation of the system 65 on the assumption that the dispatcher's channel selecting relays are controlled directly by the master relay MR instead of by the line relay L⁰.

In Fig. 2C, a combination bank of relays, composed of relays A, B, C and D and relays 70 75

X, Y and Z, is so arranged in a circuit, as to make it necessary that thirty operations occur in this bank of relays, in a certain pre-determined sequence before this bank of relays has completed one cycle. This permits the closing of thirty message channels, which may be used for indication purposes. This combination bank of relays (Fig. 2C) is associated with an identical location on a railroad and with identical controls 5 trol relays, as are shown for Fig. 1C, being indicated by corresponding letters having suitable distinctive exponents.

The sequence of operation of this bank of relays is such, that the first long positive impulse 15 picks up the relay ST², closing the front contact 169, which permits a portion of that long positive impulse to energize relay Z to a positive position, after which, the circuit arrangement permits the positive and negative impulses of the 20 normal stepping rate to successively energize the relays A, B, C and D to their reverse dotted positions. Upon the movement of relay D to its positive position, the circuit arrangement is such that, the next succeeding impulse, which 25 is negative, energizes the relay X to a negative position after which the relays A, B, C and D are successively operated to their normal position. Thus in like manner, at the completion of the successive operation of the relays A, B, C 30 and D to either their reverse positions, or their normal positions, a relay in the group X, Y and Z, succeeding the last operated relay in that group, is operated to its opposite position, until the relays X, Y and Z have each been operated 35 to their reverse positions and back to their normal positions, except the relay Z, which remains in its "at rest" position. The relay ST² acts as a blocking relay to hinder the relay Z from responding to its impulse of normal order, and 40 requires a long positive impulse to pick it up, closing a contact so that relay Z may respond.

The operating contacts of the ABCD group 45 of relays are the same as the group in the dispatcher's office, so that, when negative and positive impulses are alternately placed on the wire 262, the relays A, B, C and D are operated to reverse positions and when positive and negative impulses are placed on the wire 264 the relays A, B, C and D are operated to normal positions. 50 In each case, after the relays A, B, C and D have either completely reversed, or completely returned to normal, circuits are completed to the wires 263 and 264 respectively, which are then connected to the wires 262 and 264 respectively. It is deemed, that this explanation will 55 make it necessary to trace only the circuits in the group of relays X, Y and Z to the wires 262 and 264, stating that the A, B, C and D relays have operated, and again picking up the circuit at wires 263 and 265 respectively.

With the equipment at rest, the long positive impulse is impressed on the stepping wire 201, through wire 242, the negative contact 152 of relay Z, wire 245, positive contact 141, wire 253, 60 negative contact 148, to the wire 264, through the contacts of relays A, B, C and D, wire 265, negative contact 144, wire 256, through the relay ST² to the common wire 200, thus picking up the relay ST². The front contact 169 is thus 65 closed, completing a circuit through wire 259, and through the relay Z to the common wire 200, energizing relay Z to a positive position.

With the relay Z in a positive position, the next four succeeding impulses flow from the stepping wire 201, through wire 242, positive contact 70

152, wire 257, negative contact 146, wire 249, positive contact 140, wire 262, to reverse the contacts of relays A, B, C and D by their respective impulses. Relays A, B, C and D being reversed, the circuit continues through the wire 263, positive contact 154, wire 244, positive contact 142, 5 through relay X to the common wire 200, energizing the contacts of relay X with a negative impulse to a negative position.

With the relay X in a negative position, a circuit is completed from the stepping wire 201, through wire 242, positive contact 152, wire 257, negative contact 146, negative contact 140, wire 243, negative contact 147, to the wire 264, thus returning the contacts of relays A, B, C and D 15 to normal by their respective impulses. The circuit then continues through the wire 265, negative contact 148, wire 241, negative contact 150 of relay Y, to the common wire 200, thus operating the contacts of relay Y with a positive impulse to a positive position. 20

With the relay Y in a positive position, a circuit is completed from the stepping wire 201, through wire 242, positive contact 152, wire 257, positive contact 146, wire 258, positive contact 25 153, to the wire 262, to reverse the contacts of relays A, B, C and D by their respective impulses. The circuit then continues through wire 263, positive contact 154, wire 244, negative contact 142, wire 254, positive contact 155, through relay 30 Z to the common wire 200, thus operating the contacts of relay Z with a negative impulse to a negative position.

With the relay Z in a negative position, a circuit is completed from the stepping wire 201, 35 through wire 242, negative contact 152, wire 245, negative contact 141, wire 264, thus returning the contacts of relays A, B, C and D to normal by their respective impulses. The circuit is then continued through the wire 265, negative contact 40 148, wire 247, positive contact 150, wire 248, negative contact 143, wire 260, through relay X to common wire 200, thus operating the contacts of relay X with a positive impulse to a positive position. 45

With relay X in a positive position, a circuit is completed from the stepping wire 201, through wire 242, negative contact 152, wire 245, positive contact 141, wire 253, positive contact 148, to wire 262, to reverse the contacts of relays A, B, C and D by their respective impulses. The circuit then continues through wire 263, negative contact 154, 50 wire 251, positive contact 149, wire 250, through relay Y to common wire 200, thus operating the contacts of relay Y with a negative impulse to a negative position. 55

Thus one cycle comprising thirty operations of the relays in this combination bank has been completed. Of these thirty operations the relays X, Y and Z have made six while the relays A, B, C and D have completed six times four 60 namely twenty-four operations.

For the purpose of showing the thirty message channels obtainable with the combination of connections for the message channel selecting relays, as illustrated in Fig. 2C, reference will be 65 made to Fig. 3, in which the positions of the relays are represented by positive and negative signs arranged with three in the left column and four in the right as are the relays X, Y, Z and A, B, C, D, respectively, in Fig. 2C. In other words, a positive sign represents a contact in the right hand or positive position, and a negative sign represents a contact in the left hand or negative position, as heretofore explained. These 70 75

symbolic representations of the positions of contacts, are so arranged that their position in respect to each other represent contacts on relays as shown in Fig. 2C, which have corresponding positions in the drawings, for instance as follows:—positive sign 266 represents contact 145 in a positive position, negative sign 267 represents contact 151 in a negative position, positive sign 268 represents contact 156 in a positive position, positive sign 269 represents contact 159 in a positive position, negative sign 270 represents contact 162 in a negative position, positive sign 271 represents contact 165 in a positive position, and a negative sign 272 represents contact 168 in a negative position. Thus, the positive and negative signs as included under combination 1¹ (see Fig. 3) represent a set of contacts on the relays A, B, C and D, and X, Y and Z, which will give one message channel when assuming this given combination of positions. In other words, the contacts on said relays, which operate sequentially as heretofore described, are represented diagrammatically under the combinations 1², 2², 3², 4², etc. up to 30² such that each successive movement of relay contacts is represented in the diagram by successive combinations.

By way of illustration, the specific representation as shown by combination 8² of Fig. 3 is completely shown in diagrammatical form in Fig. 3A. In this drawing Fig. 3A, the relays and the contacts are given reference symbols to correspond with the drawing Fig. 2C, having suitable exponents to distinguish them. However, in each case, the facts represented are identical, and may be enumerated, as follows:—

(1) The 8² diagram means that this combination is set up by the eighth movement of relay contacts in response to their respective impulses after the system has been initiated;

(2) The positive and negative signs represent the positions of the contacts after the relays have thus assumed the eighth combination of positions;

(3) The dotted line through the positive and negative signs represents the particular contacts which must be connected in series to constitute the message channel chosen for that particular combination. Each of the three enumerated facts is clearly set forth diagrammatically in Fig. 3A.

The symbolic showing in Fig. 3 serves peculiarly adaptable for describing and setting forth the thirty individual message channels that may be obtained by seven relays. As has been heretofore explained in connection with Fig. 1A and 1C, when a circuit is closed through two successive contacts in series, which are assuming like positions, a circuit is closed but once during a complete cycle. This is also true of the message channels for the way station shown in Fig. 2C, if this rule of determining message channels is applied to both columns of relays used in Fig. 2C, it will be noted from Fig. 3 that in nearly every case the channel circuit (represented by a dotted line) includes successive like polarity signs in both columns, the reason why this is not necessary for all cases will presently be explained.

As there is but one movement of relay contacts in the XYZ group of relays as compared to the four movements of the ABCD group of relays, then we may term these positions assumed by the XYZ group, the group characteristic, and the positions assumed by the ABCD group the individual characteristic. Referring to Fig. 3, the groups of combinations have been designated by the letters XYZ having suitable exponents. It

is noted that the group characteristics of groups XYZ¹, XYZ², XYZ³, XYZ⁴, XYZ⁵ and XYZ⁶ are alternately two positive contacts and two negative contacts respectively which contacts are selected on successively operated relays, thus giving six distinctive group characteristics.

It is necessary in the dispatcher's message channel group of relays 1 to 17 (see Fig. 1A) to have an odd number of relays, in order that the group could complete a cycle of operation. To meet a similar requirement, for the message channel selecting relays A, B, C and D, one relay from the group XYZ has been operated to complete the number of operations in each half cycle to an odd number.

In choosing the individual characteristic, two contacts which operate in succession are selected to be connected in series. However, it will be noted, that with the group characteristic contacts (relays X, Y and Z of Fig. 3) connected in series with the individual characteristic contacts (relays A, B, C and D), that a combination is obtainable so that the combination of the group characteristic is such, that its sign completes the number of signs for the individual characteristic to 5, thus making possible five combinations for each group characteristic. For this reason only contacts of three relays are required for certain message channels as clearly shown by the conventional showing in Fig. 3.

Let us consider more specifically the combination 15², which has a group characteristic of two positive contacts. A circuit is carried through these two positive group characteristic contacts (relays X, Y and Z) and through the last positive contact (contact of relay D) in the individual characteristic. This positive individual characteristic contact does not change when combination 16² is completed, however, the group characteristic has changed to negative, thus breaking the temporarily closed message channel. Thus by using distinctive group characteristics, in combination with four distinctive individual characteristics, five distinctive combinations are obtainable for each group characteristic.

Although there are but thirty combinations obtainable with 7 relays, grouped as illustrated, it is to be understood that the total number of relays may be decreased or increased and operated on the same underlying principle, and that the number of combinations will be correspondingly changed, rendering the grouping adaptable for specific requirements.

It will be noted that the message channel shown in combination 30², is the message channel which is normally completed while the system is at rest, hence this message channel may be used for initiation purposes. Such a message channel is needed at each and every way station.

In embodying these principles for selecting message channels, in the present invention as shown in Fig. 2C the combination 30² (Fig. 3) is used for initiation purposes, and the combinations 2², 3², 4² and 5² (Fig. 3) are used for message channels over which to control the relays SR², SMR² and DR², and to give an OS indication from the track relay TR² respectively.

The relay IN² is so constructed that it has a slow releasing period, which is greater than the length of time that is required for the system to complete one cycle. Thus, as the relay TR² changes its position the contact 273 momentarily closes a circuit which energizes the relay IN², as is obvious from the drawings. As the release period of the relay IN² is greater than the length

of time required for the operation of one cycle of the system, then it is always assured that the system will complete at least one cycle after the relay TR^2 has changed positions, thus the OS indication is insured of being indicated to the dispatcher, this on the assumption that the OS condition will persist for at least one time cycle.

With the system at rest, the message wire 202 is connected to common through a message channel as obtained in combination 32^2 , when the contact 173 is picked up due to momentary energization of relay IN^2 . This initiation message circuit for the dispatcher's office has been heretofore described, so that the initiation circuit at the way station as shown in Fig. 2C need only be traced from the message wire as follows:—from message wire 202 , through wire 255 , negative contact 156 , wire 252 , negative contact 151 , wire 274 , negative contact 180 , wire 275 , front contact 179 , to the common wire 200 , thus initiating the system. The OS indication, or indication of change of the position of the track relay TR^2 , is now ready to be transmitted over the combination as set up in Fig. 3, namely combination 5^2 .

After the message channel selecting relays have been stepped along in synchronism, with the message channel selecting relays at the dispatcher's office, until this fifth channel is set up, then the following circuit is completed for the OS indication:—negative battery from battery 270 , back contact 181 , wire 277 , positive contact 168 , wire 278 , positive contact 145 , wire 246 , positive contact 156 , wire 255 , through the message wire 202 to the dispatcher's office, through positive contact 28 , wire 237 , negative contact 31 , wire 232 , positive contact 181 , negative contact 95 , positive contact 98 , negative contact 85 , positive contact 81 , negative contact 77 , positive contact 73 , negative contact 69 , positive contact 65 , negative contact 61 , positive contact 57 , negative contact 53 , positive contact 49 , positive contact 45 , through the OS relay to the common wire 200 . Thus contact 185 is energized to a negative position illuminating the indicating lamp I.

Let us again assume the system to be at rest, and that the dispatcher wishes to reverse the switch TSW^2 so that the east bound traffic may be routed into the passing siding of PS^2 . To accomplish this result the dispatcher moves the lever SML to a left hand position, which initiates the system and steps the message channel selecting relays in the way station as shown in Fig. 2C, in synchronism with the message channel selecting relays in the dispatcher's office, in a manner heretofore described, until the third message channel is set up, at which time a control impulse is sent to the relay SMR^2 . This control impulse flows through a circuit in the dispatcher's office as heretofore described, to the way station over the message wire 202 , to the relay SMR^2 through a circuit traced as follows:—from the message wire 202 , through the wire 255 , positive contact 156 of relay Z, wire 246 , positive contact 145 of relay X, wire 278 , negative contact 168 of relay D, positive contact 165 of relay C, positive contact 162 of relay B, negative contact 159 of relay A, wire 285 , through the relay SR^2 to the common wire 200 . Thus the signal relay SR^2 is energized with positive potential. When the message channel relays have been stepped along until the fourth message channel has been set up, a circuit is completed in the dispatcher's office which places a positive impulse upon the stepping wire 202 as heretofore explained which in turn is placed upon the relay DR^2 at the way station shown in Fig. 2C through a circuit traced as follows:—from the message wire 202 , through wire 255 , positive contact 156 of relay Z, wire 246 , positive contact 145 of relay X, wire 278 , negative contact 168 of relay D, negative contact 165 of relay C, wire 283 , through the relay DR^2 , to the common wire 200 . Thus the relay DR^2 is energized with positive potential, which causes its polar contact to move to a positive position. With the polar contacts of relays SR^2 and DR^2 in a positive position the signal SE^2 is cleared, allowing east bound traffic to proceed over the reversed switch TSW^2 onto the passing siding PS^2 . The message channel selecting relays step along until they have completed two cycles.

Having thus shown, and described, several specific embodiments of a rather involved and comprehensive system, for carrying out certain functions, it is desired to be understood that the particular arrangement of devices and circuits illustrated need not be adhered to, but that many changes, modifications and additions may be made, in the individual devices as well as their co-ordination with each other, without departing from the scope or spirit of the invention as demanded by the scope of the appended claims.

What we claim is:—

1. In a train dispatching system of the wayside signal control type, the combination with a large number of wayside signals located along the railway track and each controlled by traffic conditions ahead, of means for controlling said signals distinctively over the same line wires comprising, a bank of relays in the dispatcher's office, a bank of relays at each of a plurality of way stations, means for operating the relays of each bank sequentially in a particular order, and over an uninterrupted line circuit, in such a way that corresponding relays of all the banks are operated synchronously and so that corresponding relays of all banks at all times assume corresponding positions, and a plurality of message circuits for controlling said signals closed sequentially and each including the same line wire and including contacts of corresponding relays of the dispatcher's office bank and a particular way station bank.

Now let us consider that the dispatcher wishes to clear the signal SE^3 . To accomplish this, the

2. In a train dispatching system of the wayside signal control type, the combination with a large number of wayside signals each controlled by traffic conditions ahead located along the railway track, of means for controlling said signals distinctively over the same line wires comprising, a bank of relays in the dispatcher's office, a bank of relays at a particular way station, means for operating the relays of each bank sequentially in a particular order in such a way that corresponding relays of both banks are operated synchronously and so that corresponding relays of the two banks at all times assume corresponding positions, and a plurality of message circuits for controlling said signals subject to traffic conditions ahead closed sequentially and each including the same line wire and including contacts of corresponding relays of the dispatcher's office bank and a particular way station bank.
3. In a train dispatching system of the wayside signal control type, the combination with a large number of wayside signals located along the railway track, of means for controlling said signals distinctively over the same line wires comprising, a bank of stepping and channel selecting relays in the dispatcher's office, a bank of channel selecting relays at a particular way station, normally inactive stepping means for operating the relays of each bank sequentially in a particular order in such a way that corresponding relays of both banks are operated synchronously and so that corresponding relays of the two banks at all times assume corresponding positions, means for rendering said stepping means active to operate said channel selecting relays through a specific plural number of cycles of operation, and a plurality of message circuits for controlling said signals closed sequentially and each including the same line wire and including contacts of corresponding relays of the dispatcher's office bank and said way station bank.
4. In a train dispatching system of the wayside signal control type, the combination with a large number of wayside signals located along the railway track, of means for controlling said signals distinctively over the same line wires comprising, a bank of channel selecting relays in the dispatcher's office, a bank of channel selecting relays at each of a plurality of way stations, normally inactive stepping means including an uninterrupted wire running from the office to each way-station for operating the relays of each bank sequentially in a particular order in such a way that corresponding relays of all banks are operated synchronously and so that corresponding relays of all banks at all times assume corresponding positions, means controllable from any way station and from said dispatcher's office for rendering said stepping means active to operate said channel selecting relays through a specific number of cycles of operation, and a plurality of message circuits for controlling said signals closed sequentially and each including the same line wire and including contacts of corresponding relays of the dispatcher's office bank and a particular way station bank.
5. In a train dispatching system of the wayside signal control type, the combination with a large number of wayside signals located along the railway track, of means for controlling said signals distinctively over but two line wires and a common wire comprising, a bank of channel selecting relays in the dispatcher's office, a bank of channel selecting relays at each of a plurality of
- of way stations, normally inactive stepping means for operating the relays of each bank sequentially in a particular order in such a way that corresponding relays of all banks are operated synchronously and so that corresponding relays of all banks at all times assume corresponding positions, means for rendering said stepping means active to operate said channel selecting relays through a specific plural number of cycles of operation, a plurality of message circuits for transmitting OS indications and controlling signals each including the same line wire and including contacts of corresponding relays of the dispatcher's office bank and a particular way station bank.
6. In a train dispatching system of the wayside signal control type, the combination with a large number of wayside signals located along the railway track, of means for controlling said signals distinctively over only two line wires and a common wire comprising, a bank of channel selecting relays in the dispatcher's office, a bank of channel selecting relays at each of a plurality of way stations, normally inactive stepping means for operating the relays at each bank sequentially in a particular order in such a way that corresponding relays of all banks are operated synchronously and so that corresponding relays of all banks at all times assume corresponding positions, means controllable from any way station and from said dispatcher's office for rendering said stepping means active to operate said channel selecting relays through a specific plural number of cycles of operation, a plurality of message circuits for transmitting OS indications and controlling signals each including the same line wire and including contacts of corresponding relays of the dispatcher's office bank and a particular way station bank.
7. The method of controlling any one of a plurality of distant wayside signals of a railway distinctively over the same line wire, which consists in a chain of relays at a dispatcher's office and another chain of relays at a distant way station, in causing the relays of the two chains to be operated sequentially in synchronism so that corresponding relays of the two chains assume corresponding positions at all times and in operating said relays through complete cycles when operating, and in controlling said signals subject to traffic conditions in advance thereof distinctively and separately over the same line wire and corresponding contacts of corresponding relays of the two relay chains.
8. In a train dispatching system of the wayside signal control type, the combination with a large number of wayside signals located along the railway track, of means for controlling said signals distinctively over the same line wires comprising, a bank of relays at a dispatcher's office, a bank of relays at a distant way station, stepping means for operating the relays of both banks sequentially in a particular order in synchronism and in such a way that corresponding relays of both relay banks assume corresponding positions at all times and operate until the cycle of operation is completed at which point said stepping means is locked up, a slow-acting relay for unlocking said stepping means and a plurality of message circuits for controlling said signals closed sequentially and each including the same line wire and including contacts of corresponding relays of the dispatcher's office bank and the way station bank.
9. In a train dispatching system of the wayside

signal control type, the combination with a large number of wayside signals located along the railway track, of means for controlling said signals distinctively over the same line wires comprising, 5 a bank of relays at a dispatcher's office, a bank of relays at a distant way station, stepping means for operating the relays of both banks sequentially in a particular order in synchronism and in such a way that corresponding relays of both relay 10 banks assume corresponding positions at all times and operate until the cycle of operation is completed at which point said stepping means is locked up, synchronizing means for normally and automatically bringing said relays in step and re- 15 starting said stepping means once after each initiation of the system, whereby said system operates through at least two cycles of operation for each initiation, and a plurality of message circuits for controlling said signals closed sequentially and each including the same wire and including contacts of corresponding relays of the dispatcher's office bank and the way station bank. 20

10. In a train dispatching system of the wayside signal control type, the combination with a large number of wayside signals located along the railway track, of means for controlling said signals distinctively over the same line wires comprising, a bank of relays at a dispatcher's office, a bank of relays at a distant way station, 25 stepping means for operating the relays of both banks sequentially in a particular order in synchronism and in such a way that corresponding relays of both banks assume corresponding positions at all times and operate until the cycle of 30 operation is completed at which point said stepping means is locked up, synchronizing means including a slow acting relay for bringing said relays in step and restarting said stepping means, a plurality of message circuits for controlling said 35 signals closed sequentially and each including the same line wire and including contacts of corresponding relays of the dispatcher's office bank and the way station bank, and means for energizing said slow-acting relay and initiating operation of said stepping means. 40

11. In a train dispatching system of the wayside signal control type, the combination with a large number of wayside signals located along the railway track, of means for controlling said signals distinctly over the same line wires comprising, a bank of relays at a dispatcher's office, a bank of relays at a distant way station, stepping means for operating the relays of both banks sequentially in a particular order in synchronism and in such a way that certain relays 50 of both relay banks assume certain positions at certain non-recurring times and the relays of the banks operate until the cycle of operation is completed at which point said stepping means is locked up, a slow-acting relay for unlocking said stepping means, and a plurality of message circuits for controlling said signals closed sequentially and each including the same line wire and including contacts of corresponding relays 55 of the dispatcher's office bank and the way station bank another slow-acting relay which so long as it assumes its de-energized condition while having its winding energized applies current to said first mentioned slow-acting relay, and a contact on said another slow-acting relay for controlling the re-energization of said first mentioned slow-acting relay at the end of the subsequent 60 cycle of operation of said relay banks. 70

12. In a centralized traffic controlling system 75 for railroads; a distant track switch; a switch

machine for operating said track switch; and means for controlling said switch machine from a central office comprising; a series of relays in said central office, a corresponding series of relays at said distant track switch, one line relay only 5 associated with each of said series of relays, a line circuit extending between said central office and said distant track switch for connecting said line relays in a series circuit uninterruptible except at said central office, means for controlling the 10 energization of said line circuit only from said central office, circuits for interconnecting each of said series of relays with its respective one line relay to cause the relays of each series to be sequentially energized upon successive energiza- 15 tions of its one line relay, thereby causing corresponding relays of the two series of relays to be energized simultaneously when said line circuit is energized, and a message circuit for controlling said switch machine available when a particular 20 pair of said corresponding relays of said two series of relays is energized. 25

13. In a centralized traffic controlling system for railroads; a distant track switch; a switch machine for operating said track switch; and means for controlling said switch machine from a central office comprising; a series of relays in said central office, a corresponding series of relays at said distant track switch, one line relay only 30 associated with each of said series of relays, a line circuit extending between said central office and said distant track switch for connecting said line relays in a series circuit uninterruptible except at said central office, means for controlling the energization of said line circuit only from 35 said central office, circuits for interconnecting each of said series of relays with its respective one line relay to cause the relays of each series to be sequentially energized upon successive energizations of its one line relay, thereby causing 40 corresponding relays of the two series of relays to be energized simultaneously, a slow acting relay associated with each of said series of relays which prevents the initiation of operation of said series unless said slow acting relay is first operated, means for controlling said slow acting relay, and a message circuit including but one additional line wire for controlling said switch machine rendered available for controlling said switch machine when a particular pair of corresponding relays of said two series of relays is 45 energized. 50

14. In a centralized traffic controlling system for railroads; a distant track switch; a switch machine for operating said track switch; and means for controlling said switch machine from a central office comprising; a series of polar relays of the two position type at the central office, a corresponding series of polar relays of the two position type at said distant track switch, means 55 for successively operating the corresponding pairs of relays of said two series of relays from their normal to their reverse position during the first half cycle of operation and operating successively corresponding pairs of relays back to 60 their normal position during the second half of the cycle of operation, the relays of each pair being operated simultaneously, and a distinct message circuit connecting said central office and said track switch completed upon each operation 65 of a pair of relays, whereby there are rendered available two message circuits for each relay of a series during each cycle of operation of said system. 70

15. In a centralized traffic controlling system 75

for railroads; a distant track switch; a switch machine for operating said track switch; and means for controlling said switch machine from a central office comprising; a series of polar relays 5 of the two position type at the central office, a corresponding series of polar relays of the two position type at said distant track switch, means for successively operating the corresponding pairs of relays of said two series of relays from their 10 normal to their reverse position during the first half cycle of operation and operating successively corresponding pairs of relays back to their normal position during the second half of the cycle of operation, the relays of each pair being 15 operated simultaneously, and a plurality of message circuits in number equal to twice the number of relays in each series, each message circuit of which includes the contacts of two adjacent relays, closed sequentially during operation of said 20 relays, and means for controlling said switch machine over one of said message circuits.

16. An impulse counting group of relays comprising, a series of two position polar counting relays of the first order, a series of two position 25 polar counting relays of the second order, and interconnecting circuits to effect repeat operation through the series of relays of the first order for each operation of one of said relays of the second order, whereby the total number of impulses 30 which may be absorbed by said counting group of relays is equal to twice the product of the counting relays of the first order and the number of counting relays plus one of the second order.

35 17. For use in a centralized traffic controlling system for railways, a bank of polar relays of the two-position stick type, means for successively operating the relays each to its opposite position, and then each back to its first position 40 by energizing a circuit with energy of alternating polarities.

18. For use in centralized traffic controlling systems for railways, in combination, a chain of two-position polar stick type relays, an energizing 45 circuit for the first relay of the chain including its own point of one polarity, each succeeding relay having an energizing circuit including its own point of one polarity, the point of the next preceding relay of the same polarity, and points 50 of alternate polarities, respectively, of the remaining preceding relays.

19. For use in centralized traffic controlling systems for railways, in combination, a chain of two-position polar stick type relays, an energizing 55 circuit for the first relay of the chain including its own point of one polarity, each succeeding relay having an energizing circuit including its own point of one polarity, the point of the next preceding relay of the same polarity, and points 60 of alternate polarities, respectively, of the remaining preceding relays, a second energizing circuit for each relay relatively arranged as above, but the case of each relay, relating to the point of such relay of opposite polarity to that recited 65 above.

20. In a control means of the selector type; a bank of selecting relays; means for subjecting said bank of relays to a series of spaced current impulses; and an energizing circuit for each relay, the energizing circuit for each relay being completed only upon the operation of a preceding 70 relay but being effective to cause the operation of

its relay only upon the reception of the next impulse of said series of impulses following that impulse which caused the operation of the preceding relay, and the operation of each relay making its energizing circuit immune to subsequent current impulses, whereby each relay responds only to its respective impulse in said series of impulses. 5

21. In a control means of the selector type; a bank of selecting relays; means for subjecting said bank of relays to a series of spaced current impulses; an energizing circuit for each relay of the bank, the energizing circuit for each relay being completed only upon the operation of a preceding relay but being effective to cause the operation of its relay only upon the reception of the 15 next impulse of said series of impulses following that impulse which caused the operation of the preceding relay, and the operation of each relay making its energizing circuit immune to subsequent current impulses, whereby each current impulse 20 causes operation of but one of the relays of the bank of relays, and whereby the relays are operated in succession; and channel circuits sequentially closed by said bank of relays. 25

22. In a control means of the selector type, in combination, a bank of selecting relays, an energizing circuit for each relay, means for subjecting the bank to a series of spaced current impulses, the energizing circuit for each relay being completed only after the immediately preceding 30 relay has been operated, and the operation of each relay making its energizing circuit immune to subsequent current impulses, whereby each current impulse causes operation of but one of the relays of the bank of relays, and the relays are 35 operated in succession, another energizing circuit for each relay of the bank, each relay being a two-position relay, said another circuits being related to each other as are the first said energizing circuits, but related, in each case, to the other position of the relay than the position to which the first said energizing circuits are related. 40

23. In combination, a first line wire connecting an office and a station, a movable device at said station, means operating in response to a change 45 in the position of said device to deliver a starting impulse to said first line wire, a second line wire connecting said office and station, a bank of stepping relays in said office responsive to said starting impulse for delivering another impulse to said 50 second line wire, means at the station responsive to said other impulse to deliver to said first line wire an indication impulse under the control of said device, and means at the office selectively controlled by said indication impulse. 55

24. In a centralized traffic control system for railroads, a control office, a plurality of way stations, a stepping circuit, automatic impulsing means for placing impulses on said stepping circuit, step-by-step means at each of said stations 60 and said control office all operated in synchronism by the application of said impulses to said stepping circuit, traffic controlling devices at each way station, and a starting circuit extending between said control office and said way stations capable 65 of being closed at each station when a change in the position or condition of one or more of said traffic controlling devices occurs at a station if said automatic impulsing means is not in operation. 70
